UNITED STATES PATENT OFFICE.

EDWIN BURHORN, OF HOBOKEN, NEW JERSEY.

COOLING-TOWER.

1,118,267.

Specification of Letters Patent. Patented Nov. 24, 1914.

Application filed July 1, 1907. Serial No. 381,719.

To all whom it may concern:

Be it known that I, EDWIN BURHORN, a citizen of the United States, and resident of Hoboken, in the county of Hudson and State of New Jersey, have invented certain new and useful Improvements in Cooling-Towers, of which the following is a specification.

My invention relates to improvements in cooling towers, and particularly to that class of towers in which the natural air currents are brought into contact with the liquid to be cooled. Efficiency in this form of tower requires that the liquid to be cooled be finely divided while in contact with the atmosphere and that the distribution be uniform. The simple perforated pan heretofore in use has been found effective, for the reason that where the perforations are small enough to sub-divide the water sufficiently, they clog very quickly, while if the perforations are sufficiently large to avoid clogging, the liquid descends in streams of considerable size, and is not properly cooled, and as the air currents tend to drive the falling liquid to one side of the tower, an irregular distribution results.

The objects of my invention are to secure an even distribution of the liquid to be cooled, to avoid clogging, and to properly divide the liquid for the maximum cooling effect. Also to afford a novel arrangement of water passages and connections whereby the apparatus may be adjusted to varying conditions of weather.

Other objects will appear in the herein-after following description.

I attain these objects by the device shown in the accompanying drawings, in which—
Fig. 1 is an elevation of my cooling tower showing two of the decks. Fig. 2 is a cross-section of my preferred form of drip-bar. Fig. 3 is a view of one longitudinal side of the same. Figs. 4, 5 and 6, are views in cross-section of optional forms of the drip-bar. Fig. 7 is an elevation of an optional form of my device. Fig. 8 is a longitudinal view of optional forms for the edge of the drip-bar. Fig. 9 is a plan view of the regulating device applied in one of the pans.

Similar letters refer to similar parts throughout the several views.

Upon a suitable framework of which two of the supports A A are shown, I arrange

decks of my improved drip-bars one above the other. These decks are supported by girders, B B B, secured to the supporting frame work. Each layer of these drip bars, I term a deck and the spacing, number and size of these decks are determined by the capacity and other conditions under which the tower operates. I prefer to arrange the several decks or layers of drip bars at an angle to the decks above and below, as I find that a better distribution of the liquid is thereby obtained in windy weather, as the falling liquid driven to leeward will on entering the drip bars run to windward and thus afford more equal distribution.

C is the main supply pipe from which are branched the distributing pipes c, c', c'', from which the liquid to the upper deck is discharged into the drip bars b. I prefer to form these drip-bars b as narrow troughs with closed ends, and having their edges b⁴ indented. The pipes c, c', are each formed in their under sides with distributing apertures located above the several drip bars.

The precise form of the indentations b⁴ may be varied as desired. I prefer to use the sharp indentations shown in Fig. 3, but the curved indentations or the rectangular indentations shown in Fig. 8 may in some cases be employed to advantage.

The operation of the device is as follows: The liquid to be cooled is supplied through the main supply pipe C to the auxiliary supply pipes c, c' from which it is discharged into the drip bars b of the upper deck. When the liquid in the drip bars b of the upper deck reaches the lower line of the indent b⁴ in the side edges, it will run over the edges and, spreading out on the sides of the bars, will be finely divided and drip down in fine spray into the drip bars E of the deck below. The descending liquid will fill the drip bars E of the lower deck, and the operation above described will be continued as before to the bottom of the tower. The quantity of liquid supplied to the drip bars is regulated by suitable means so that the liquid will be supplied in sufficient quantity to overflow from each drip bar as desired. The reason for indenting the upper edge b⁴ of the drip bars is to properly distribute the liquid, as where a straight edge is used, the slightest deviation from a perfect level will concentrate the overflow, at one point, and so destroy the

result desired. By reason of the open top of the drip bars, the indents b^4 will not clog with foreign matter as would the old form of perforation in the bottom of the pan. 5 The space between the drip bars is made sufficiently great to avoid clogging.

In order to effect a more perfect distribution of the descending shower in windy weather, I find it desirable in some cases to 10 employ a collecting pan d above each deck of drip bars, to the upper one of which the liquid to be cooled is supplied from the pipe C through the branch pipes C' , from which it flows into the pan d above the drip 15 bars as shown in Fig. 7, and through perforations d^4 in the bottom of the pan into the drip bars from which it falls into the pan of the deck below, where it is again distributed in the same manner. The perforations d^4 in the bottom of the pan d are arranged directly over each drip bar. It will thus be obvious that each pan will serve as a rectifying device in maintaining a uniform distribution on each deck, regardless 25 of the deflection of the shower from the vertical between the decks.

According to one branch of this invention, I provide separate liquid supply pipes at the several decks of my device, by means 30 whereof the tower may be fed from any deck as shown in Figs. 1 and 7, so as to enable the operator to cut out superfluous decks in cold weather. Thus, in Fig. 1 the supply pipe c is shown above the topmost 35 deck and the supply pipe c^2 over the next lower deck; while in Fig. 7 supply pipe c' is shown over the topmost deck and the supply pipe c^2 over the second deck. In each case each of the supply pipes is provided with an independent valve c^3 . By this combination of elements, passages and valves it is possible to cause a greater or less number of decks to be put into operation as desired. Thus, we have a water connection 45 for supplying warm water directly to the topmost deck, and we have another connection for supplying warm water directly to a deck lower than the topmost deck, and we have the controlling means or valves c^3 50 whereby may be determined to which deck the warm water is to be supplied. Thereby the apparatus is able to be adjusted to weather conditions, and, for example, in case of freezing weather over-cooling of the 55 water may be prevented by supplying it, not to the topmost deck, but to a deck lower down, so that the danger of cooling below

the freezing point and clogging the tower with ice is avoided.

An optional means for regulating the quantity of liquid supplied to the drip bars from the pan above is shown in Fig. 9 in which are shown flat metal strips d' laid upon the floor of the pan d to regulate the size of the openings in the bottom of the pan d when desired. These metal strips d' are provided with a series of holes d^5 registering with those in the pan. A movement of the strips d' from the point where the holes d^5 register with the holes in the bottom of the pan will reduce the size of the openings in the bottom of the pan d , and regulate the discharge. A hand wheel g and screw g' may be provided for operating the strips d' in the usual manner. 75

Having thus described my invention, what I claim is:

1. In a cooling tower of the type wherein water passes downward by gravity and is drawn off at the bottom, the combination of an upright frame, a series of cooling decks carried by said frame spaced substantially vertically from each other, means comprised in each deck for receiving water to be cooled and transmitting it in distributed form to the deck beneath; and means for causing a greater or less number of decks to be put in operation, comprising a water connection for supplying warm water directly to the topmost deck, another connection for supplying warm water directly to a deck beneath the topmost deck, and controlling means or valves for determining to which deck the water shall be supplied, whereby the apparatus can be adjusted to weather conditions, and overcooling prevented in freezing weather. 80

2. In a device of the character described, a frame, a plurality of horizontal decks supported thereby each deck comprising a series of drip bars each in the form of a trough, and a collecting pan, each collecting pan being provided with discharge apertures arranged in rows and registering with the drip bars below it, substantially as shown and described. 95

Signed at the city of New York in the county of New York and State of New York this 28th day of June A. D. 1907.

EDWIN BURHORN.
